STUFFED FOOD PRODUCT

Gladys B. Levine, Hamlet, N.C.

Application September 21, 1956, Serial No. 43,036

Term of patent 14 years

(Cl. D82—2)

I claim:

The ornamental design for a stuffed food product, as shown.
